(57) **CLAIM**

The ornamental design for a corner of a panel, as shown and
described.

DESCRIPTION

FIG. 1 is a perspective view of a first embodiment of a
corner of a panel in an environment of use;
FIG. 2 is an enlarged detailed view of the boxed area 2 in
FIG. 1;

FIG. 3 is a front view thereof;

FIG. 4 is a right side view thereof;

FIG. 5 is a top view thereof;

FIG. 6 is a bottom view thereof;

FIG. 7 is a perspective view of a second embodiment of a
corner of a panel in an environment of use;

FIG. 8 is an enlarged detailed view of the boxed area 8 in
FIG. 7;

FIG. 9 is a front view thereof;

FIG. 10 is a right side view thereof;

FIG. 11 is a top view thereof;

FIG. 12 is a bottom view thereof;

FIG. 13 is a perspective view of a third embodiment of a
corner of a panel in an environment of use;

FIG. 14 is an enlarged detailed view of the boxed area 13 in
FIG. 13;

FIG. 15 is a front view thereof;

FIG. 16 is a right side view thereof;

FIG. 17 is a top view thereof;

FIG. 18 is a bottom view thereof;

FIG. 19 is a perspective view of a fourth embodiment of a
corner of a panel in an environment of use;

FIG. 20 is an enlarged detailed view of the boxed area 20 in
FIG. 19;

FIG. 21 is a front view thereof;

FIG. 22 is a right side view thereof;

FIG. 23 is a top view thereof; and,

FIG. 24 is a bottom view thereof.

All broken line portions of the figures are included to show
environments and form no part of the claimed design.
